GOLF BALL WINDING MACHINE

Raphael Atti, Cliffside Park, N. J.

Application December 19, 1946, Serial No. 717,177

10 Claims. (Cl. 242—3)

1

This invention relates to golf ball winding machines.

Among the objects of the present invention, it is aimed to provide an improved golf ball winding machine in which a substantially uniform tension is maintained on the string or strip of rubber before and while it is being wound in the formation of the ball consisting not only in a combination of tension exerting devices which supplement one another to produce not only a predetermined degree of tension, but also a smooth uniform tension throughout the winding operation irrespective of the diameter of the ball in the process of formation.

These and other features, capabilities and advantages of the invention will appear from the subjoined detail description of one specific embodiment thereof illustrated in the accompanying drawings, in which

Fig. 1 is a front elevation of a machine made according to the present invention.

Fig. 2 is a section on the line 2—2 of Fig. 1.

Fig. 3 is a section on the line 3—3 of Fig. 1.

Fig. 4 is an enlarged fragmental plan partly in section of the ball supporting rollers.

Fig. 5 is a wire diagram of the wiring from the switches to the machine.

In the embodiment shown, there is provided a platform 1, secured to the upper ends of the upright plates 2 and 3. The front plate 3, see Figs. 1 and 2, extends slightly above the upper face of the platform 1, and therefore defines the position of the cheek plate 4 extending upwardly from the platform 1 adjacent to the rear face of the front plate 3. This cheek plate 4 is secured to the platform 1 and front plate 3 by any suitable well known means.

Extending from the front face of the plate 3 there is provided a stub shaft 5 for securing the spool 6 on which is wound a predetermined supply of rubber string or rubber strip about $\frac{1}{16}$ of an inch wide by .020 of an inch in thickness. The spool 6 may be secured in place on the stub shaft 5 by any suitable well known means. From the spool 6 the strip of rubber 7 initially is passed over the idler 8 and from the idler 8 passed on to the large wooden idler 9. Preferably as shown, in order to guide the rubber band 7 to and from the idler 8, there are provided a pair of guiding pins 10 and 11 extending upwardly from the block 12 secured to the front plate 3 below the idler 8, such pins 10 and 11 being disposed adjacent to but slightly spaced from the entrance end of the idler 8 as shown in Fig. 1. Spaced from the discharge end of the idler 8 and also

2

extending upwardly from the block 12 there are provided the two guiding pins 13 and 14. The two pairs of pins 10, 11 and 13, 14 are aligned relative to the parallel annular flanges 15 and 16, see Fig. 2, so that the strip 7 may be definitely guided from the spool 6 to the groove 17 between the flanges 15 and 16. As the strip 7 passes over the idler 8, it will be compressed by the roller 18 rotatably mounted on the stub shaft 19 formed on the lever 20, fulcrumed on the stub shaft 21 extending from the front face of the plate 3. The lever 20 has an arm 22 provided with a finger piece 23 to be engaged by the operator to lift the roller 18 from the idler 8 and facilitate threading the rubber strip 7 between the pairs of pins 10, 11 and 13, 14, and between the idler 8 and roller 18.

The free end of the lever 20 has pivotally connected thereto the rod 24 having a supporting disk 25 at the lower end thereof to receive slotted weights 26, 26. The number and size of weights 26 mounted on the disk 25 depends upon the pressure to be exercised by the roller 18 on the idler 8. Preferably the idler 8 and roller 18 are composed of suitable polished steel. The large idler 9, as shown, is preferably secured to the sides of the drum 27 which also is preferably composed of steel, having a polished cylindrical surface. This drum 27 and idler 9 concentrically secured to one another are preferably journaled on the stub shaft 28 extending from the front face of the wall 3. Any suitable means may be provided to anchor the idler 9 and drum 27 in place on the stub shaft 28.

The rotation of the drum 27 and in turn of the idler 9 is retarded by the lever 29 resting on the drum 27, the lever 29 being pivotally connected by the screw 30 to the front face of the wall 3. The free end of the lever 29 has pivotally connected thereto the rod 31 which is provided with a disk 32 at the lower end thereof to receive slotted weights 33, 33. Preferably the lever 29 is composed of bronze to cooperate with the steel drum 27 so that a predetermined pressure may be exercised on the drum 27 to retard the rotation thereof without effecting undue wear on the same.

From the idler 9 the rubber strip 7 extends to the groove 34 in the V-shaped idler 35 mounted on the shaft 36. The groove 34 is disposed between the ends of the converging faces of the conical surfaces 37 and 38 of the V-shaped idler 35. The shaft 36 of the idler 35 in the present instance is journaled in the cheek plate 4 and extends through the parallel supporting plates

39 and 40. The plates 39 and 40 extend upwardly from the upper face of the platform 1 being spaced from one another with the plate 40 adjacent to the cheek plate 4 and the plate 39 spaced therefrom and disposed rearwardly of the plate 4. Preferably as shown, the plates 39 and 40 are connected to one another by the cross plate 41. The plates 39 and 40 may be secured in place on the platform 1 by any suitable well known means.

From the groove 34 the rubber strip 7 is passed to the core of the ball to be wound. Such core is not shown but is well known in the art and is preferably composed of a small rubber ball in the technique known as a pill, frequently as small as three-quarters of an inch in diameter, and sometimes more or less in diameter according to the price of the ball to be produced. These pills in the technique of manufacturing golf balls are frequently frozen to a temperature of about 50° or more below zero F. in order to obtain a satisfactory hard surface.

After the strip 7 is attached to this pill, the pill is positioned between the conical faces 37 and 38 of the roller 35 and the cylindrical face of the driven roller 42. This roller 42 is fixed on the shaft 43, journalled in the bearings 44 mounted in alined openings formed in the cheek plate 4 and plate 40. This shaft 43 has mounted thereon the cam 45 disposed between the plates 39 and 40, the shaft also being journalled in the bearings 46 secured in the plate 39. The shaft 43 extends to the rear of the plate 39 and has fixed thereon the sheave or pulley 47. The shaft 43 with the pulley 47, cam 45 and roller 42 are fixed to one another and slidably as well as rotatably mounted in the bearings 44 and 46. As the pulley 47 is rotated in turn to rotate the shaft 43, the cam 45 engaging the cam rollers 48 and 49 cause the shaft 43 to reciprocate or oscillate back and forth. The rollers 48 and 49 are journalled on the pins 50 and 51 formed on the blocks 52 fixed on the rod 53 supported in the plates 39 and 40.

The pulley 47 preferably is connected by the V-belt 54 to the pulley 55 on the shaft 56 of the motor 57. Excellent results have been achieved when the V-belt 54 is about three-eighths of an inch in thickness and the grooves of the pulleys 47 and 55 are designed to receive a V-belt of this thickness.

In order to anchor the ball 58 being formed in position between the idler 35 and roller 42, there is provided the convex peripheral faced idler 59 journalled on the shaft 60 fixed to the bar 61 slideable on the facing plate 62 secured to the front face of the cheek plate 4. The bar 61 is guided in its vertical movement by the parallel bars 63 and 64 secured to the facing plate 62. This idler 59 is weighted by the weight 65 mounted on the lever 66 which is fulcrumed on the pin 67 extending from the cheek plate 4. The lever 66 is anchored to the pin 67 by any suitable well known means. The arm 66 is in turn pivotally connected to the slideable bar 61 by the pin 68.

The weight 65 is provided with a set screw 69 in order to anchor it to the lever 66 according to the weight to be exercised, the weight 65 being otherwise slidably mounted on the lever 66. By this combination of weights, to wit, the weight 65 of the lever 66, the weights 26 of the lever 20, and the weights 33 of the lever 29, a predetermined tension may be effected on the rubber strip 7, and in turn on the ball 58 as the strip 7 is being wound on the ball 58. It has been found, as an instance, that the idler 9 and its associated weights 33 sup-

plement the weighted roller 18. It has been found, as an instance, that since the strip 7 is wider than it is thick, while it is passing from the spool 6 to the idler 9, a twist in the same when passing between the idler 8 and roller 19 may cause a jump. Without the idler 9, such jump would be transmitted to the ball 58 and cause the same to depart from its theretofore regular rotation. The idler 9, due to its extended surface, irons out such jump, absorbing the same so that the theretofore regular rotation will not be interrupted. This regular or uniform rotation of the ball 58 will be achieved when the tension in the strip 7 is maintained substantially constant and the roller 43 is oscillated at an even velocity, which in turn will effect a substantially uniform basket weave, the particular type of weave so necessary to produce a substantially perfect sphere.

For a conventional golf ball having a diameter of 1.60 inches, excellent results have been achieved when the motor 57 was set to rotate at a speed of 1750 revolutions per minute, the weight exercised by the roller 18 approximated four ounces, the weight exercised by the lever 29 approximated four ounces, the weight exercised by the roller 59 approximated sixteen ounces, and the diameter of the peripheral groove 17 approximated four and one-half inches.

The control for the operation of the motor 57 and in turn for the rotation of the driven roller or drum 42 is also unique and a feature of the present invention.

The start button 70, as an instance, has two contacts 71 and 72 to be bridged by the button 70. The contact 71 is connected by the conductor 73 to the contact 74, which in turn is connected by the conductor 75 to the main lead 76. The contact 72, on the other hand, is connected by the conductor 77 to the contact 78 from which current can pass to the contact 79 when the button 80 bridges the gap between the contacts 78 and 79. The contact 79, in turn, is connected by the conductor 81 to the contact 82 of the mercury switch 83 which when closed bridges the gap between the contact 82 and the contact 84. The contact 84, in turn, is connected by the conductor 85 to the contact 86 of the microswitch 87, which when closed bridges the gap between the contact 86 and the contact 88. The contact 88 in turn is connected by the conductor 89 to the coil 90 of the magnetic switch which in turn is connected by the conductor 91 to the other main lead 92.

The mercury containing tube 93 of the mercury switch 83, as shown in Fig. 1, is preferably mounted on the arm 94 fixed to the pivot pin 95, which in turn is fixed to the arm 96, having the rubber strip 7 engaging the roller 97. The pin 95, in the present instance, is journalled in the cheek plate 4. Preferably, temporarily to anchor the arms 95 and 96 of the mercury switch 83 in circuit making position, there is provided a spring finger 98 secured to the cheek plate 4 into engagement with which the arm 96 may be moved and frictionally held in such anchored position, the position shown in Fig. 1.

The microswitch 87 in turn is preferably mounted on the block 99 secured to the rear face of the cheek plate 4 on which in turn is secured the pivot pin 100 for the lever 101 having the arm 201 positioned to engage the microswitch 87 and having the arm 102 extending into the path of movement of the stop head 103 of the screw 104 secured to the block 105 extending from the front face of the plate 61.

From the foregoing, it will appear that when

the microswitch 87 is closed, that is, is not actuated into open position by the arm 201, the mercury switch 83 is closed, and the stop button 80 is in its normal closed position, then upon actuating the start button 70 into closed position, it being in normally open position, then through the wiring just traced the coil 90 will be energized.

Upon energizing the coil 90, the six switches 106, 107, 108, 109, 110 and 111 will be actuated into closed position, and upon the subsequent release of the start button 70, whereupon it will return to its normal open position, that shown in Fig. 5, the current to the motor 57 will now pass, it then passing from the main lead 76 across the switch 108 to the conductor 112, and across the switch 111 to the conductor 113 which is connected to the motor 57. From the motor 57, in turn, the current will pass through the conductor 114 to the switch 109, from the switch 109 by means of the conductor 115 to the switch 106 and then to the other main lead 92. While the circuit to the motor 57 is thus closed, the coil 90 will remain energized, the current to and from it passing from the main lead 92 and conductor 91 to the coil 90, and from the coil 90 through the conductor 89, microswitch 87, conductor 85, mercury switch 83, conductor 81, normally closed stop switch 80, conductor 116, switch 110, conductor 117, switch 107, and conductor 75 to the other main lead 76.

When it is desired manually to stop the machine, that is, bring the motor 57 to rest, it will only be necessary to press the switch button 80 to actuate it into open position, when the circuit from the main leads 76 and 92, not only to the coil 90 of the magnetic switch, but also to the motor 57, will be interrupted.

In turn, after the machine has been started by initially actuating the starting switch button 70 and sufficient tension has been built up in the rubber strip 7, the roller 97 may be pushed off the spring arm 98 when the roller 97 will rest on the strip 7 between the idler 9 and the roller 35 in closed position of the mercury switch 83.

Should the strip 7 break or become exhausted, that is, end, then the arm 96 will descend into the position where it will open the mercury switch 83 and interrupt the circuit of the coil 90 and of the motor 57.

In turn, on the other hand, after the ball 58 has increased in diameter to the size prescribed, which is determined by the adjustment of the screw 104, the slide 61 will rise to the point where the head 103 of the screw 104 engages and deflects the arm 102 sufficiently to actuate and open the microswitch 87, when again the circuit to the coil 90 and motor 57 will be interrupted.

Preferably the walls 39 and 40 cooperate with two rearwardly extending walls, not shown, to form a liquid tight container with the platform 1 to receive lubricating oil up to the desired height, preferably so that at least a part of the cam 45 will be running in oil.

Preferably the rubber strip extends from the supply spool 6, then between the two guide pins 11 and 18, then between the idler 9 and roller 10, then between the guide pins 14 and 13, then under the idler 9 engaging at least one-half and between one-half and two-thirds of the periphery of the groove 17, then passing under the roller 91 of the mercury switch 83, and then under the V-roller 35, that is, between the V-roller 35 and driven roller 42 to the ball 58 in the process of being wound.

It is obvious that various changes and modifi-

cations may be made to the details of construction without departing from the general spirit of the invention as set forth in the appended claims.

I claim:

1. The combination of a supply spool of rubber strip, a small idler, a large idler, a freely rotatable V-shaped supporting roller, a driven cylindrical roller disposed adjacent to said V-shaped supporting roller and receiving the ball element being wound, the rubber strip extending from the supply spool to the small idler, then to the large idler, and finally to the ball element being wound and causing the small idler and large idler to be rotated by the surface contact of the rubber strip with the peripheries of said idlers, a pressure roller engaging the rubber strip and pressing it into engagement with said small idler, a bearing drum fixed to said large idler, a pressure exercising arm engaging said drum, a slide vertically slidable, a roller mounted on said slide and engaging the ball element being wound, and a second pressure exercising arm pivotally connected to said slide, said pressure roller and two pressure exercising arms cooperating with the friction created between said strip and the periphery of said large idler to effect a uniform predetermined stretching tension in said strip before it is wound upon the ball element being wound, and the extensive surface of said large idler functioning to iron out any jumps that might be transmitted to the strip when so being stretched before it passes to the ball element being wound.

2. The combination of a supply spool of rubber strip, a small idler, a large idler, a freely rotatable V-shaped supporting roller, a driven cylindrical roller disposed adjacent to said V-shaped supporting roller and receiving the ball element being wound, the rubber strip extending from the supply spool to the small idler, then to the large idler, and finally to the ball element being wound and causing the small idler and large idler to be rotated by the surface contact of the rubber strip with the peripheries of said idlers, a pressure roller engaging the rubber strip and pressing it into engagement with said small idler, a bearing drum fixed to said large idler, a pressure exercising arm engaging said drum, a slide vertically slidable, a roller mounted on said slide and engaging the ball element being wound, a second pressure exercising arm pivotally connected to said slide, said pressure roller and two pressure exercising arms cooperating with the friction created between said strip and the periphery of said large idler to effect a uniform predetermined stretching tension in said strip before it is wound upon the ball element being wound, and the extensive surface of said large idler functioning to iron out any jumps that might be transmitted to the strip when so being stretched before it passes to the ball element being wound, a slidably mounted shaft on which said driven roller is secured, and cam means cooperating with said shaft to reciprocate said roller to and fro and thereby effecting a basket weave by the strip on the ball element being wound.

3. The combination of a supply spool of rubber strip, a small idler, a large idler, a freely rotatable V-shaped supporting roller, a driven cylindrical roller disposed adjacent to said V-shaped supporting roller and receiving the ball element being wound, the rubber strip extending from the supply spool to the small idler, then to the large idler, and finally to the ball element being wound and causing the small idler and large idler to be rotated by the surface contact of the rubber strip

with the peripheries of said idlers, a pressure roller engaging the rubber strip and pressing it into engagement with said small idler, a bearing drum fixed to said large idler, a pressure exercising arm engaging said drum, a slide vertically slid able, a roller mounted on said slide and engaging the ball element being wound, a second pressure exercising arm pivotally connected to said slide, said pressure roller and two pressure exercising arms cooperating with the friction created between said strip and the periphery of said large idler to effect a uniform predetermined stretching tension in said strip before it is wound upon the ball element being wound, and the extensive surface of said large idler functioning to iron out any jumps that might be transmitted to the strip when so being stretched before it passes to the ball element being wound, a slidably mounted shaft on which said driven roller is secured, cam means cooperating with said shaft to reciprocate said roller to and fro and thereby effecting a basket weave by the strip on the ball element being wound, a pivotally mounted switch arm resting on said strip after sufficient stretching tension has been created in the same, an electric motor drivingly connected to said driven roller, and an electric circuit for said motor including a mercury switch, said mercury switch mounted on said switch arm and operable to interrupt the current in the circuit of said motor when the strip is exhausted or broken and the switch arm descends.

4. The combination of a supply spool of rubber strip, a small idler, a large idler, a freely rotatable V-shaped supporting roller, a driven cylindrical roller disposed adjacent to said V-shaped supporting roller and receiving the ball element being wound, the rubber strip extending from the supply spool to the small idler, then to the large idler, and finally to the ball element being wound and causing the small idler and large idler to be rotated by the surface contact of the rubber strip with the peripheries of said idlers, a pressure roller engaging the rubber strip and pressing it into engagement with said small idler, a bearing drum fixed to said large idler, a pressure exercising arm engaging said drum, a slide vertically slid able, a roller mounted on said slide and engaging the ball element being wound, a second pressure exercising arm pivotally connected to said slide, said pressure roller and two pressure exercising arms cooperating with the friction created between said strip and the periphery of said large idler to effect a uniform predetermined stretching tension in said strip before it is wound upon the ball element being wound, and the extensive surface of said large idler functioning to iron out any jumps that might be transmitted to the strip when so being stretched before it passes to the ball element being wound, a slidably mounted shaft on which said driven roller is secured, cam means cooperating with said shaft to reciprocate said roller to and fro and thereby effecting a basket weave by the strip on the ball element being wound, an electric motor drivingly connected to said driven roller, an electric circuit for said motor including a microswitch, a pivotally mounted lever having two arms, and an adjustable screw mounted on said slide and engaging and actuating one arm of said lever when the ball element being wound has increased to the size predetermined in turn to cause its other arm to actuate said microswitch to interrupt the current in the circuit of said motor.

5. The combination of a supply spool of rubber

strip, a small idler, a large idler, a freely rotatable V-shaped supporting roller, a driven cylindrical roller disposed adjacent to said V-shaped supporting roller and receiving the ball element being wound, the rubber strip extending from the supply spool to the small idler, then to the large idler, and finally to the ball element being wound and causing the small idler and large idler to be rotated by the surface contact of the rubber strip with the peripheries of said idlers, a pressure roller engaging the rubber strip and pressing it into engagement with said small idler, a bearing drum fixed to said large idler, a pressure exercising arm engaging said drum, a slide vertically slid able, a roller mounted on said slide and engaging the ball element being wound, a second pressure exercising arm pivotally connected to said slide, said pressure roller and two pressure exercising arms cooperating with the friction created between said strip and the periphery of said large idler to effect a uniform predetermined stretching tension in said strip before it is wound upon the ball element being wound, and the extensive surface of said large idler functioning to iron out any jumps that might be transmitted to the strip when so being stretched before it passes to the ball element being wound, a slidably mounted shaft on which said driven roller is secured, cam means cooperating with said shaft to reciprocate said roller to and fro and thereby effecting a basket weave by the strip on the ball element being wound, a pivotally mounted switch arm resting on said strip after sufficient stretching tension has been created in the same, an electric motor drivingly connected to said driven roller, an electric circuit for said motor including a mercury switch, said mercury switch mounted on said switch arm and operable to interrupt the current in the circuit of said motor when the strip is exhausted or broken and the switch arm descends, a magnetic switch electrically connected to said circuit, and a main control having a stop and start switch electrically connected to said circuit whereby the current in the circuit may be initially closed when said start switch is actuated and said mercury switch is closed and in turn whereby the current in the circuit may be interrupted when said stop switch is actuated.

6. The combination of a supply spool of rubber strip, a small idler, a large idler, a freely rotatable V-shaped supporting roller, a driven cylindrical roller disposed adjacent to said V-shaped supporting roller and receiving the ball element being wound, the rubber strip extending from the supply spool to the small idler, then to the large idler, and finally to the ball element being wound and causing the small idler and large idler to be rotated by the surface contact of the rubber strip with the peripheries of said idlers, a pressure roller engaging the rubber strip and pressing it into engagement with said small idler, a bearing drum fixed to said large idler, a pressure exercising arm engaging said drum, a slide vertically slid able, a roller mounted on said slide and engaging the ball element being wound, a second pressure exercising arm pivotally connected to said slide, said pressure roller and two pressure exercising arms cooperating with the friction created between said strip and the periphery of said large idler to effect a uniform predetermined stretching tension in said strip before it is wound upon the ball element being wound, and the extensive surface of said large idler functioning to iron out any jumps that might be transmitted to the strip when so being stretched before it

passes to the ball element being wound, a slidably mounted shaft on which said driven roller is secured, cam means cooperating with said shaft to reciprocate said roller to and fro and thereby effecting a basket weave by the strip on the ball element being wound, an electric motor drivingly connected to said driven roller, an electric circuit for said motor including a microswitch, a pivotally mounted lever having two arms, an adjustable screw mounted on said slide and engaging and actuating one arm of said lever when the ball element being wound has increased to the size predetermined in turn to cause its other arm to actuate said microswitch to interrupt the current in the circuit of said motor, a magnetic switch electrically connected to said circuit, and a main control having a stop and start switch electrically connected to said circuit whereby the current in the circuit may be initially closed when said start switch is actuated and said microswitch is closed and in turn whereby the current in the circuit may be interrupted when said stop switch is actuated.

7. The combination of a supply spool of rubber strip, a small idler, a large idler, a freely rotatable V-shaped supporting roller, a driven cylindrical roller disposed adjacent to said V-shaped supporting roller and receiving the ball element being wound, the rubber strip extending from the supply spool to the small idler, then to the large idler, and finally to the ball element being wound and causing the small idler and large idler to be rotated by the surface contact of the rubber strip with the peripheries of said idlers, a pressure roller engaging the rubber strip and pressing it into engagement with said small idler, a bearing drum fixed to said large idler, a pressure exercising arm engaging said drum, a slide vertically slidably, a roller mounted on said slide and engaging the ball element being wound, a second pressure exercising arm pivotally connected to said slide, said pressure roller and two pressure exercising arms cooperating with the friction created between said strip and the periphery of said large idler to effect a uniform predetermined stretching tension in said strip before it is wound upon the ball element being wound, and the extensive surface of said large idler functioning to iron out any jumps that might be transmitted to the strip when so being stretched before it passes to the ball element being wound, a slidably mounted shaft on which said driven roller is secured, cam means cooperating with said shaft to reciprocate said roller to and fro and thereby effecting a basket weave by the strip on the ball element being wound, a pivotally mounted switch arm resting on said strip after sufficient stretching tension has been created in the same, an electric motor drivingly connected to said driven roller, an electric circuit for said motor including a mercury switch and a microswitch, said mercury switch mounted on said switch arm and operable to interrupt the current in the circuit of said motor when the strip is exhausted or broken and the switch arm descends, a pivotally mounted switch lever having two arms, an adjustable screw mounted on said slide and engaging and actuating one arm of said lever when the ball element being wound has increased to the size predetermined in turn to cause its other arm to actuate said microswitch to interrupt the current in the circuit of said motor, a magnetic switch electrically connected to said circuit, and a main control having a stop and start switch electrically connected to said circuit whereby the current in

the circuit may be initially closed when said start switch is actuated and said mercury and microswitches are closed and in turn whereby the current in the circuit may be interrupted when said stop switch is actuated.

8. The combination of a supply spool of rubber strip, a small idler, a large idler, a freely rotatable V-shaped supporting roller, a driven cylindrical roller disposed adjacent to said V-shaped supporting roller and receiving the ball element being wound, the rubber strip extending from the supply spool to the small idler, then to the large idler, and finally up between said V-shaped supporting roller and said driven cylindrical roller to the ball element being wound and causing the small idler and large idler to be rotated by the surface contact of the rubber strip with the peripheries of said idlers, a pressure roller engaging the rubber strip and pressing it into engagement with said small idler, a bearing drum fixed to said large idler, a pressure exercising arm engaging said drum, a slide vertically slidably, a roller mounted on said slide and engaging the ball element being wound, a second pressure exercising arm pivotally connected to said slide, said pressure roller and two pressure exercising arms cooperating with the friction created between said strip and the periphery of said large idler to effect a uniform predetermined stretching tension in said strip before it is wound upon the ball element being wound, and the extensive surface of said large idler functioning to iron out any jumps that might be transmitted to the strip when so being stretched before it passes to the ball element being wound, a slidably mounted shaft on which said driven roller is secured, and cam means cooperating with said shaft to reciprocate said roller to and fro and thereby effecting a basket weave by the strip on the ball element being wound.

9. The combination of a supply spool of rubber strip, a small idler, a large idler, a freely rotatable V-shaped supporting roller, a driven cylindrical roller disposed adjacent to said V-shaped supporting roller and receiving the ball element being wound, the rubber strip extending from the supply spool to the small idler, then to the large idler, and finally up between said V-shaped supporting roller and said driven cylindrical roller to the ball element being wound and causing the small idler and large idler to be rotated by the surface contact of the rubber strip with the peripheries of said idlers and a pressure roller engaging the rubber strip and pressing it into engagement with said small idler, a slide vertically slidably, a convex faced roller mounted on said slide and engaging the ball element being wound, and a pressure exercising arm pivotally connected to said slide, said pressure roller and pressure exercising arm cooperating with the friction created between said strip and the periphery of said large idler to effect a uniform predetermined stretching tension in said strip before it is wound upon the ball element being wound, and the extensive surface of said large idler functioning to iron out any jumps that might be transmitted to the strip when so being stretched before it passes to the ball element being wound.

10. The combination of a supply of rubber strip, a small idler, a large idler, a freely rotatable V-shaped supporting roller, a driven cylindrical roller disposed adjacent to said V-shaped supporting roller and receiving the ball element being wound, the rubber strip extending from the supply to the small idler, then to the large

11

idler, and finally up between said V-shaped supporting roller and said driven cylindrical roller to the ball element being wound and causing the small idler and large idler to be rotated by the surface contact of the rubber strip with the peripheries of said idlers, a first pressure exercising means engaging the rubber strip and pressing it into engagement with said small idler, a bearing drum fixed to said large idler, a second pressure exercising means engaging said drum, a slide vertically slid able, a third pressure exercising means mounted on said slide and engaging the ball element being wound, said first, second and third pressure exercising means cooperating with the friction created between said strip and the

15

12

periphery of said large idler to effect a uniform predetermined stretching tension in said strip before it is wound upon the ball element being wound, and the extensive surface of said large idler functioning to iron out any jumps that might be transmitted to the strip when so being stretched before it passes to the ball element being wound, a slidably mounted shaft on which said driven roller is secured, and cam means cooperating with said shaft to reciprocate said roller to and fro and thereby effecting a basket weave by the strip on the ball element being wound.

RAPHAEL ATTI.
